UNITED STATES PATENT OFFICE.

NANCY GOODE JENNINGS, OF APPOMATTOX, VIRGINIA.

BEATER AND MIXER.

1,073,133.

Specification of Letters Patent. Patented Sept. 16, 1913.

Application filed July 2, 1912. Serial No. 707,343.

To all whom it may concern:

Be it known that I, NANCY GOODE JENNINGS, a citizen of the United States, residing at Appomattox, in the county of Appomattox and State of Virginia, have invented new and useful Improvements in Beaters and Mixers, of which the following is a specification.

The invention relates to kitchen utensils and has for an object to provide a beating and mixing device.

The invention embodies, among other features, a device more particularly adapted for use in beating and mixing food products, the device being conveniently adapted for beating and mixing eggs.

In the further disclosure of the invention reference is to be had to the accompanying drawings, in which similar characters of reference denote corresponding parts in all the views, and in which:

Figure 1 is a perspective view of my device showing the same in applied position; Fig. 2 is a vertical sectional view showing the interior construction and the manner of supporting the device; Fig. 3 is a horizontal transverse sectional view taken on the line 3—3 in Fig. 2; and Fig. 4 is a horizontal transverse sectional view taken on the line 4—4 in Fig. 2.

Referring more particularly to the views, I employ a supporting frame 10, terminating at one end in a depending member 11 adapted for reception in a socket 12 formed with the walls of a container 13, a bracket 14 being rigidly secured or formed with the container 13 adjacent the under side thereof and having a laterally extending member 15 spaced from the under side of the container for the purpose of rigidly securing the container to a table top or the like, a thumb screw 16 having threaded connection with the member 15 and adapted to engage the under side of the table top to rigidly secure the container thereto, a thumb screw 17 being mounted to extend through a wall of the socket 12 formed with the container 13, with an end of the thumb screw adapted to engage the member 11 of the frame 10 to rigidly secure the supporting frame 10 to the container 13.

The supporting frame 10 has formed therewith a sleeve like vertically extending member 18 arranged in the vertical plane of the container 10 and above the same, a rod 19 being mounted to slidably extend through

the sleeve-like member 18 and into the container 13, a seat 20 being preferably formed in the bottom of the container to receive the lower end of the rod 19, thus retaining the same in rigid position within the container.

A stud 21 is mounted to project from the sleeve-like member 18 and mounted to turn on the stud 21 is a toothed wheel 22, provided with a suitable handle 23, the mentioned toothed wheel being adapted to mesh with a toothed wheel 24 keyed to the upper end of the rod 19, the said toothed wheel 22 being also adapted to mesh with a toothed wheel 25 keyed to a frame 26 revolvably mounted on the rod 19, a collar 27 being mounted on the rod 19 to support the frame 26 in revolvable position thereon as shown in Fig. 2, it being readily understood that when the wheel 22 is rotated, the rod 19 will be operated in one direction and the frame 26 in the opposite direction, the frame 26 being of an inverted U-shape so that the said frame will revolve around the rod 19, within the container 13 when the wheel 22 is operated.

A series of horizontally extending blades 28 are arranged to project laterally from the rod 19, the said blades being revolvable with the rod and equi-distantly spaced apart as shown, the mentioned blades consisting more substantially of vertical body portions 29 and horizontal ends 30, each blade being twisted at its medial portion 31 and each blade being formed of a single piece of material such as stamped metal, the medial portion of each blade being twisted as mentioned, so that each blade will present a side portion and an end portion.

Mounted to project inwardly from the frame 26 are a series of blades 32, similar to the blades 28 and arranged to extend in opposite directions to the blades 28, the mentioned blades 32 being mounted on the frame 26 to operate between the blades 28 as shown, the ends of the blades 32 being, however, spaced from the rod 19 and the blades 28, the blades 32 at the points where they join with the frame 26, being vertical and at their extremities horizontal, the said blades being twisted at their medial portions and constructed substantially the same as the blades 28 on the rod 19.

In the use of my device, the container 13 is first rigidly secured to a table top by means of the clamping member 15 including the thumb screw 16, and the product

to be beaten or mixed is placed within the container 13, after which the handle 23 is grasped and the wheel 22 is rotated, thus, through the medium of the toothed wheel 24, operating the rod 19 and consequently the blades 28, in one direction, within the container and causing the frame 26, through the medium of the toothed wheel 25, to rotate in the opposite direction, the blades 10 32 being adapted to rotate with the frame 26, thus thoroughly stirring, mixing and beating the contents of the container 13. A spout 33 is preferably formed on the container 13 at a point approximately opposite to the point of connection of the frame 10 with the container and when it is desired to pour or remove the contents of the container therefrom, this can be accomplished by using the frame 10 as a handle and tilting the container so that the contents of the container will flow outwardly through the spout 33.

By constructing the blades 28 and 32 as mentioned heretofore the contents of the container will be thoroughly mixed and beaten when the blades are set in motion in the manner described, the mentioned blades 28 and 32, owing to their peculiar construction and relative arrangement, forming efficient elements whereby, through the rotation of the rod 19 and frame 26, the desired result is accomplished.

It will be readily understood that my device can be used for various purposes and that if desirable the container 13 can be dispensed with and the device held in the hand with the blades arranged to depend in any suitable vessel, the contents of which are to be beaten and mixed.

It will be further understood that I do not limit myself to the particular construction disclosed in the drawings and de-

scribed in the specification, the scope of the invention being defined by the appended claims.

Having thus described my invention, I claim:

1. In a device of the class described, the combination with a container, of a supporting frame mounted thereon, means for securing the supporting frame on the said container, a rod journaled on the supporting frame and depending in the container, a beater frame journaled on the said rod and depending in the container, means mounted on the said supporting frame for operating the said rod and for rotating the rod in one direction and the beater frame in the opposite direction, and similar blades projecting from the lower ends of the said rod and said beater frame, the said blades being twisted at their medial portions with the blades on the rod spaced equidistantly apart to receive the blades on the beater frame therebetween. 65

2. In a device of the class described, the combination with a supporting frame, of a rod journaled thereon, a U-shaped beater frame, means for rotating the said rod in one direction and the said beater frame in the opposite direction, and blades projecting horizontally from the said rod and the said beater frame, the said blades being twisted at their medial portions so that one-half of each blade will lie in a vertical 75 plane and the other half of each blade will lie in a horizontal plane. 75

In testimony whereof I affix my signature in presence of two witnesses.

NANNIE GOODE JENNINGS.
